UNITED STATES PATENT OFFICE.

WARREN B. HOWE, OF CHICAGO, ILLINOIS.

PASTING-MACHINE.

SPECIFICATION forming part of Letters Patent No. 588,484, dated August 17, 1897.

Application filed September 28, 1896. Serial No. 607,150. (No model.)

To all whom it may concern:

Be it known that I, WARREN B. HOWE, of Chicago, in the county of Cook and State of Illinois, have invented certain new and useful Improvements in Pasting-Machines; and I do hereby declare that the following is a full, clear, and exact description thereof, reference being had to the accompanying drawings, and to the letters of reference marked thereon, which form a part of this specification.

This invention relates to improvements in machines intended for fastening together by adhesive materials the blanks or parts of paper or strawboard boxes or cartons; and the object of the invention is to enable the work of supplying adhesive material and the placing together of the blanks to be carried on with rapidity and with perfect accuracy in the finished work.

The invention consists in the matters hereinafter described, and pointed out in the appended claims.

The machine herein shown embraces as its main or principal features a tubular blank-holder, which acts as a support or guide for the blanks at the time the adhesive material is being applied thereto and to hold the parts of the box in proper relative position while drying, and a paste-applying device movable periodically into contact with the blanks resting in the tubular holder and acting to apply adhesive material to the blanks as the latter are placed successively in the holder by hand.

A machine embodying my invention is applicable in the manufacture of boxes of any kind which are capable of being folded flat at the time the paste is applied, the same being more especially adapted for use in the making of what are known as "knockdown" boxes. The machine herein shown is, however, more especially designed for the making of cartons, such as are used for packing candy and other articles in barrels or pails and which consist of a plurality of sector-shaped cells or compartments formed by radial walls connected at their outer ends by equal and similar sections adapted to fold upon their lines of juncture with each other simultaneously with the folding together of

the radial walls, such cartons being adapted to be collapsed or folded flat for transportation or storage and expanded for use in the manner of a fan to form a substantially circular carton with radial partitions. 55

In the accompanying drawings, Figure 1 is a side elevation of a pasting-machine embodying my invention. Fig. 2 is a front elevation, on an enlarged scale, of a portion of the machine, the tubular blank-holder being shown in section on the line 2 2 of Fig. 1. Fig. 3 is an enlarged detail of a portion of one of the adjustable guides in the blank-holder, showing the arrangement of the spring-retarding arms. Fig. 4 is a horizontal sectional view of the parts shown in Fig. 3, taken on the line 4 4 thereof. Fig. 5 is a plan view of the machine with the power-applying mechanism and a portion of the link broken away. 70 Fig. 6 is a vertical section taken through the paste receptacle and reservoir and through the paste-carrier on the line 6 6 of Fig. 5. Fig. 7 is a vertical section of the mechanism, taken on the line 7 7 of Fig. 5. Fig. 8 is a 75 detached sectional view of the compressible link with its spring removed. Fig. 9 is a horizontal sectional view of the blank-holder, paste-carrier, and paste receptacle and reservoir on the line 9 9 of Fig. 5 and showing 8c the paste-carrier in different positions. Fig. 10 is a view of the carton after the paste has been applied by the machine with some of the compartments opened. Fig. 11 is a view similar to Fig. 2, showing a portion of the 85 machine, but with the adjustable plates of the paste-carrier and of the blank-holder arranged for pasting a different-shaped box.

The machine is shown as mounted on a table consisting of a horizontal top A and four legs attached thereto. A rectangular portion A' extends laterally from the table-top and supports a standard A², in which is journaled a shaft B, which has rigidly fastened to its right-hand end an ordinary belt-wheel B' and on its left-hand end a gear-pinion B², which meshes with a gear-wheel C', rigidly and centrally fastened to a shaft C, which is journaled at its right-hand end in a bearing in the standard A² directly above the bearing for the shaft 95 B. The shaft C is also journaled in a bearing in the curved standard A³, projecting up 100

wardly and forwardly from the rear of the table A, and carries at its left-hand end a crank C², to which is pivoted a connecting rod or link, shown as consisting of two parts D D', through which motion is transmitted to a swinging frame E, to which is attached the paste-carriers F, by which paste is transferred from a paste-receptacle H to the blanks held in a tubular blank-holder K. The said link, as shown, is made yielding or compressible lengthwise, and for this purpose consists of the screw-threaded eyebolt D, which can slide to a limited extent in the tubular socket D', which is pivoted at its forward end between two ears E' on the swinging frame E. The socket D' has a slot D² in its upper surface, in which plays a pin D³, projecting upwardly from the forward end of the bolt D, as clearly shown in Figs. 7 and 8. A strong helically-coiled spring D⁴, surrounding the bolt D, is confined between the rear end of the socket D' and a nut D⁵ on the screw-threaded portion of the bolt D, which is held in place by a lock-nut D⁶. The frame E, as seen in Fig. 5, is rectangular in shape and is carried by parallel arms E², pivoted thereto and projecting upwardly from the ends of a pair of parallel rock-shafts E³, which are mounted on bearings carried by the lugs A⁴ on the table. These rock-shafts E³ might be journaled directly in the lugs, but I prefer to have bearing-cavities in their ends, with which coöperate the ends (shown as conical) of bolts E⁴, inserted through the lugs A⁴ and held by the lock-nuts E⁵ at any desired adjustment. It will be readily seen from this construction that when the shaft C is rotated, the bolt D and the socket D' ordinarily operate as a rigid link, and the frame E will be carried back and forth from the two extreme positions shown in Figs. 8 and 9.

The forward portion of the frame E has rigidly fastened to the under side or integral therewith, as shown, the rectangular plate E⁶, containing the parallel longitudinal slots E⁷, (best shown in Fig. 5,) by which the paste-carriers are secured to said frame. These paste-carriers, as seen in Figs. 5 and 6, consist of plates F', which are rectangular in plan view, but of L shape in cross-sectional form, and in the downwardly-projecting portion or flanges of the plates are fastened two parallel rows of paste-applying pins F'. Said pins are brought into contact with or have their ends immersed in the adhesive material in the paste-receptacle at each backward movement of the paste-carriers and are brought into contact with or pressed against the blanks, so as to deposit on the blank the material which adheres to their ends, somewhat as ink is deposited from type in printing.

The proper angular adjustment of the plates F' on the frame E is effected as desired by screws F², which pass through the slots E⁷ and enter the top of the plates F, so as to hold them in any desired position. In the machine here illustrated it is desired to have

the paste applied on the portions of the box where the laps G' of one portion come against the ends of the radial parts G of the adjacent portion, as shown in Fig. 10. As the portions or blanks which form the carton are not rectangular, but are irregular in their shape, as shown in Fig. 5, the two brush-plates F are set at an angle to each other, as seen in said figure and as more clearly shown by the spots upon the folded boxes, showing where the paste has been applied.

The pins F² at each rearward movement of the frame E are thrust into the paste-receptacle H a fixed depth. As it is desirable that the pins shall always take up the same quantity of paste, it is necessary that the paste-receptacle always be filled to a uniform depth, and this condition is attained by the following mechanism:

The paste-receptacle H is located above the level of the paste-reservoir H², said receptacle, as herein shown, being mounted upon posts H', resting upon the bottom of the paste-reservoir, which has the form of a shallow rectangular tank. Said reservoir, as shown in Fig. 5, rests by means of posts H³ upon the top of the table. Journaled in the right-hand end of the reservoir H² is a horizontal shaft H⁴, which has secured to its right-hand end a belt-wheel H⁵, through which said shaft is driven by means of a belt J from a similar belt-wheel C³, fastened on the shaft C. To the left-hand or inner end of the shaft H⁴ is attached a disk H⁶, the lower portion of which is immersed in the paste in the reservoir H², as shown in Fig. 6. The paste-receptacle H is rectangular in shape, as seen from above, except that it has a rectangular offset portion H⁷ at the rear portion of its right-hand end, said offset portion bearing at its end against a portion of one side of the disk H⁶. It results from this construction that as the disk H⁶ is rotated and passes into the paste it will carry up the paste which adheres to it, and the adhering paste will be scraped off by the edge of the receptacle H and will flow into the said receptacle as the rotation continues, thus keeping the receptacle constantly full to overflowing, the disk H⁶ carrying upwardly and depositing the paste faster than it is removed by the paste-carrier.

To the forward end of the table A is secured the blank-holder K, which is substantially rectangular in plan view and contains within it adjustable guide bars or strips, whereby its bearing-surfaces, which engage the edges of the blanks, may be shaped so as to accommodate blanks of any desired form. The vertical rear wall K' of the tubular holder has a cross-section of the shape shown in Fig. 5 and carries two guide-strips, the first of which, L, is not adjustable, but is substantially rigid with the right-hand side of the rear wall K'. The second strip L' on said wall K' is adjustable by means of set-screws or bolts L², (shown in dotted lines in Fig. 5,) passing through the slots K² in the rear wall

K' and entering said strip L'. This strip L' is shown as adjusted to different positions in Figs. 2 and 11.

The right-hand side wall K³ has no adjustable strips; but a raised strip K⁴ furnishes a smooth flat surface against which the edges of the blanks rest and by which they are guided on this side, as shown in Fig. 5. The left-hand side wall K⁵ has mounted thereon a guide-strip L³ of the cross-sectional form shown in Fig. 5 and adjustable inwardly and outwardly by means of set-screws L⁴, which engage screw-threaded holes therein and pass through screw-threaded lugs in the wall K⁵. The front wall K⁶ has mounted therein a supplemental wall K⁷, having a cross-section as shown in Fig. 5 and adjustable backwardly and forwardly by means of thumb-nuts K⁸ on screw-threaded bolts K⁹, which are fastened to said supplemental wall K⁷ and pass through sockets in the front wall K⁶. Provision is also made for adjusting the angular position of the supplemental wall K⁷ with relation to the front wall K⁶ by means of set-screws K¹⁰ on both sides of the bolts K⁹, which engage the right and left hand ends of the wall K⁷. The supplemental wall K⁷ has at its right-hand end a raised portion or strip K¹¹, furnishing a flat guide-surface for the blanks, and at its center is an adjustable strip L⁵, similar to the strip L', similarly mounted and adjusted and acting to guide the blanks, as shown in Fig. 5. It will be seen that by this construction of the holder K, as hereinbefore described, I have obtained a structure that guides the blanks of the shape illustrated through it without allowing any shifting from the position first assumed, and also one that is capable of being adjusted so as to accommodate blanks of very different shapes.

To prevent the blanks from passing through the holder K without any resistance and to yieldingly detain them at the bottom, so that in operation the holder will always be full and those at the top will remain in proper position for the action of the paste-carrier thereon and offer sufficient resistance to the pressure of the paste-applying device to insure proper application of the paste thereto, I place in the lower end of the holder spring arms or detents M, adapted to stand normally in position to resist the downward movement of the lowermost blanks in the chute, but adapted to yield outwardly under downward pressure of the blanks from above, so as to allow the blanks to pass from the chute. As herein shown, Figs. 2 and 5, the said spring-detents consist each of a single leaf-spring secured at its upper end to one of the guide-strips L, L', L³, L⁵, K⁴, and K¹¹ and bent at an angle at its lower part, so as to extend at a downward inclination into the tubular holder. Each spring rests in a vertical groove or recess m, adapted to receive its lower end when thrust outwardly.

The means shown for attaching the springs to the guides consist of slots m', Fig. 3,

formed in the solid parts of the guides above the grooves, into which slot the upper end portions of the springs are inserted, metal pins M' being inserted in the wooden guide behind the spring to afford a more rigid support for the same. The spring-catch M on the guide-strip L³ has at its lower end a lug M², which holds the blanks at one side of the holder until released from the opposite sides. The blanks approach the lower end of the holder K, and meet with considerable resistance to their further progress from the spring-detents, which is overcome by the weight of those above them and the pressure of the paste-applying device acting thereon. As they are finally forced out at the bottom, the lug M² offering more resistance than is experienced at any other side, the box is released from that side last, so that it falls always in one position, as shown in Fig. 9.

While I have herein called the device for holding and guiding the blanks a "tubular" blank-holder, yet it is to be understood that the essential parts of such holder are the guides or guide-strips themselves, and the holder may be of skeleton form or consist of guides supported in any suitable way and need not be tubular in the sense of being a closed tube, and which latter form of holder is herein shown merely as a matter of convenience in construction.

The carton, which the machine illustrated is more especially intended to make, is shown in Fig. 10, the same consisting of a plurality of radial partitions G G, each adjacent pair of which are connected by two arc walls G² G², flexibly joined to the radial walls and to each other at a point midway between the radial walls, so that the cell formed by the two radial walls and the two arc walls may be folded flat by the outward folding of the arc walls on their lines of juncture and the bringing of the radial walls into contact with each other, as clearly seen in Fig. 10. The carton thus constructed is composed of a plurality of separate pieces, each of which forms one radial wall G and two arc walls G² G² and which is provided at its ends with flaps G' G³, forming extensions of the inner end of the radial wall and the extremity of the arc wall, so that when the said flaps are pasted to the outer faces of the radial walls of similar blanks a series of compartments will be formed, as clearly seen in said Fig. 10.

All of the compartments necessary to constitute a circular or segmental carton will be made by the use of like blanks, with the exception that the end compartment of the series will be finished by means of a flat blank G⁴, equal in length to a radial wall only and which when the carton is expanded will rest against the radial wall at the opposite end thereof, as clearly seen in dotted lines in said Fig. 10. The blanks forming the carton of the kind described are joined when in their collapsed or folded position by applying the adhesive material to the flaps G' G³ or to the

marginal parts of the arc walls against which said flaps rest and piling the blanks one upon another with their edges accurately in register. In thus piling the blanks the number 5 used for each carton is equal to the number of cells in the carton, and a single blank to form the radial wall G^4 is then applied to complete the final or terminal cell, when the carton will be finished in knockdown form and 10 may be readily expanded into its circular form. The construction of such a carton is more fully explained in the prior patent granted to F. B. Davidson February 5, 1895, No. 533,638.

15 In the operation of the machine the operator stands in front of it and has in a convenient position a supply of the two kinds of blanks above referred to—namely, the blanks forming the walls G^2 and the shorter blank 20 for forming the wall G^4 . These blanks will conveniently be placed on extensions A^5 of the table, Fig. 5, which are located at either side of the front of the machine. Assuming the blank-holder K to be filled with previously 25 pasted and folded blanks, or with a suitably-shaped filling piece or block to support the first blanks, the operator first takes a short blank and lays it on top of the pile between the upper ends of the guide-strips K^4 , K^{11} , L , 30 L' , L^3 , and L^5 . The machine is then started and the paste-carrier moved from the paste-receptacle into contact with the blanks, 35 against the upper surface of which the paste-applying pins are pressed, so as to leave an imprint of paste thereon, the paste being applied in a line at either end of the blank. The action of the paste-carrier serves also to press the entire pile of pasted blanks downwardly a short distance through the guides. 40 One of the longer blanks is then folded by the operator into the form shown in Fig. 10, the flap G' being folded against the adjacent radial wall, while the flap G^3 is left in the same plane with the outer portion of the arc 45 wall, to which it is attached. The folded blank is then placed in position on top of the pile between the guide-strips, thereby bringing the two flaps G' and G^3 against the pasted portions of the shorter blank. The 50 blank is so placed on the pile during the time the paste-carrier is moving toward the paste-receptacle and returning therefrom, and in the subsequent advance of the said paste-carrier the latter applies paste to the top surface of 55 the longer blank at the inner and outer margins of the radial wall thereof. A second long blank is then folded and placed on the first long blank, and these operations are repeated until the number of blanks added to 60 the pile equal the number of cells in the carton. The carton shown in the accompanying drawings, Fig. 10, is provided with five of such cells, and consequently consists of five of the longer or folded blanks and one short 65 blank. After the carton has thus been completed a new carton is started by placing a short blank on top of the pile without per-

mitting any paste to be applied to the last blank of the completed carton. This may be done by placing a folded blank and a short 70 blank together on the pile, or by interrupting the action of the paste-carrier long enough to add the short blank, this being done by pressing down the treadle N , which throws the hook N^2 upward into position to act on the 75 rear cross-bar of the frame E , as seen in Fig. 2. The resistance offered to the descent of the lowermost pasted blank in the pile, combined with the weight of the superposed blanks and the pressure of the paste-carrier 80 thereon in applying the paste, insures that the paste-pots shall be kept closely pressed together until the parts sufficiently adhere or the paste is dried.

As above stated, the construction of the 85 blank-holder permits the same to be employed in the making of boxes of various shapes, and the paste-carriers F being adjustable in position on the swinging frame the same may be arranged to apply the adhesive material to 90 any portion of the blanks desired, as made necessary by reason of the shape or construction of the box.

In Fig. 11 of the accompanying drawings I have shown the adjustable guides of the 95 blank-holder and the paste-carriers as arranged to operate on a box-blank of rectangular form.

While my invention is herein shown as embodied in a machine adapted for pasting cartons of the particular form shown, yet it is to be understood that it may be applied to operate on boxes of different shapes and that the details of construction in the machine may be greatly modified without departure from the 105 spirit of the invention. I do not, therefore, desire that my invention be limited to the exact form or details of construction in the machine shown and described, except so far as the features of said machine may be set 110 forth in the appended claims.

I claim as my invention—

1. A box-pasting machine comprising a blank-holder, means within the holder acting on the edges of the blanks for retarding the 115 passage of the blanks therethrough, and a reciprocating paste-carrier acting on the blanks within the holder both to apply paste to said blanks and to force them through the said holder.

2. A box-pasting machine comprising a blank-holder provided with spring-detents for retarding the passage of the blanks therethrough, and a reciprocating paste-carrier acting on the blanks to force them through 125 the holder.

3. A box-pasting machine comprising a tubular blank-holder, means within the holder acting on the edge of the blanks for retarding the passage of blanks therethrough, a reciprocating paste-carrier acting on the blanks within the holder both to apply paste to said blanks and to force them through said holder, an oscillatory frame supporting said paste-

carrier and means for giving reciprocatory motion to said frame.

4. A box-pasting machine comprising a tubular blank-holder, means within the holder 5 acting on the edges of the blanks for retarding the passage of the blanks therethrough, a reciprocating paste-carrier acting on the blanks within the holder both to apply paste to said blanks and to force them through said holder, a swinging frame which supports the same and pivoted arms movably supporting said frame.

5. A box-pasting machine comprising a tubular blank-holder, means within the holder 15 acting on the edges of the blanks for retarding the passage of blanks therethrough, a reciprocating paste-carrier, a receptacle for adhesive material and a swinging frame supporting the paste-carrier and shifting it from 20 the said receptacle into contact with the blanks, said carrier acting on the blanks within the holder both to apply paste to said blanks and to force them through the holder.

6. A box-pasting machine comprising a tubular blank-holder, means within the holder 25 acting on the edges of the blanks for retarding the passage of blanks therethrough, a receptacle for adhesive material, a paste-carrier acting on the blanks within the holder both to apply paste to said 30 blanks and to force them through the holder, both to apply paste to said blanks and to force them through the holder, a swinging horizontally-arranged frame for supporting said carrier, two pairs of swinging arms supporting said frame and means for actuating said paste-carrier.

7. A box-pasting machine comprising a holder for the blanks embracing a plurality of adjustable guide-strips, means acting on the edges of the blanks for retarding the passage 40 of the blanks through said holder and a paste-carrier acting on the blanks within the holder both to apply paste to said blanks and to force them through said holder.

8. A box-pasting machine comprising a tubular blank-holder provided with spring-detents which act on the edges of the blanks to retard the movement of the blanks through the holder and a paste-carrier acting on the blanks within the holder both to apply paste 45 to said blanks and to force them through said holder.

9. A box-pasting machine comprising a tubular holder for the blanks provided with adjustable guide-strips and provided also with 55 spring-detents which act on the edges of the blanks for retarding the movement of the blanks therethrough and a paste-carrier acting on the blanks within the holder both to apply paste to said blanks and to force them 60 through said holder.

10. A box-pasting machine comprising a blank-holder, means within the holder for retarding the passage of blanks therethrough, a receptacle for adhesive material, a reciprocating paste-carrier carried by oscillating arms from the receptacle to the blank-holder 65

and acting on the blanks within the holder both to apply paste to said blanks and to force them through said holder and means for actuating the paste-carrier embracing a crank-shaft and a connecting-rod uniting the crank with the paste-carrier.

11. A box-pasting machine comprising a blank-holder embracing guide-strips and spring-arms attached to said strips and acting 70 on the edges of the blanks for retarding the movement of the blanks through the holder and a paste-carrier acting on the blanks within the holder to apply paste to said blanks to force them through said holder.

12. A box-pasting machine comprising a blank-holder, embracing adjustable guide-strips adapted to engage the edges of the blanks and spring-detents attached to said guide-strips and acting on the edges of the 80 blanks to retard their passage through the holder and a paste-carrier acting on the blanks both to apply paste to said blanks and to force them through said holder.

13. A pasting-machine comprising a tubular blank-holder, means therein for retarding the passage of blanks therethrough, a receptacle for adhesive material, a reciprocating paste-applying device movable from the receptacle to the blank-holder, the same being 90 arranged to enter the receptacle vertically and to act vertically on the blanks in the holder, a paste-reservoir into which the paste-receptacle overflows, and means for constantly elevating the paste from the reservoir 95 into the receptacle.

14. A pasting-machine comprising a tubular blank-holder, means therein for retarding the passage of the blanks therethrough, a paste-receptacle, a reciprocating paste-carrier moving between the receptacle and the blank-holder and acting on the blanks to force them through the holder, and means for actuating the said paste-carrier connected with the same by an elastic or yielding connection. 105

15. A pasting-machine comprising a tubular blank-holder, a paste-receptacle, means therein for retarding the passage of blanks therethrough, a reciprocating paste-carrier moving both horizontally and vertically between the receptacle and the blank-holder, and acting on the blanks to force them through the blank-holder, means for actuating the said paste-carrier connected with the same by an elastic or yielding connection, and a stop 115 which can be interposed when desired to limit the movement of the paste-carrier.

16. A pasting-machine comprising a blank-holder, means therein for retarding the passage of blanks therethrough, a receptacle for adhesive material, a paste-carrier having both a horizontal and vertical reciprocatory motion from the receptacle to the blank-holder, and acting on the blanks to force them through the blank-holder, a reservoir located beneath the receptacle, a rotating disk for carrying the adhesive material from the reservoir to the 125 130

receptacle and power connections for giving reciprocating motion to said paste-carrier and for turning said disk.

17. A pasting-machine comprising a blank-
holder, means within the blank-holder for re-
tarding the passage of blanks therethrough,
a receptacle for adhesive material, a recip-
rocating paste-carrier carried by oscillating
arms which swing in vertical planes and move
the paste-carrier both vertically and horizon-
tally, said paste-carrier acting on the blanks
to force them through the holder, and means
for actuating the paste-carrier embracing a

crank-shaft and a connecting-rod uniting the
crank with the paste-carrier, said connecting-
rod embracing two sliding parts, and a spring
applied to hold them extended. 15

In testimony that I claim the foregoing as
my invention I affix my signature, in presence
of two witnesses, this 22d day of September, 20
A. D. 1896.
